UNITED STATES PATENT OFFICE.

CHARLES DECRETTE, OF NEW YORK, N. Y.

METAL-BENDING MACHINE.

1,383,751.

Specification of Letters Patent Patented Mar. 16, 1920.

Application filed September 6, 1919 Serial No. 322,013.

To all whom it may concern:

Be it known that I, CHARLES DECRETTE, a citizen of the United States, and resident of New York, in the county of New York and State of New York, have invented certain new and useful Improvements in Metal-Bending Machines, of which the following is a specification.

This invention relates to metal bending machines, and has for its main object to provide such a machine which will bend metal bars, beams, channels, et cetera, in a substantial manner so that the resultant bent member will be durable, strong, and lasting, the operation of bending being very simple and rapid.

Other objects of my invention are, to provide facilities by means of which the metal may be bent either flat or edgewise with accuracy, at any angle and at any predetermined place by one operation only, necessitating but one heating of the metal; to provide easily interchangeable bending elements in such simple and convenient way as to afford quick and accurate pressing and bending action while the metal is heated.

The above and other objects will become apparent in the description below, in which characters of reference refer to like-named parts on the drawings.

Referring briefly to the drawings, Figure 1 is a plan view of my machine, showing the general arrangement of parts.

Fig. 2 is a front view of the machine, partly in section on the line 2—2 of Fig. 1.

Fig. 3 is a transverse sectional view of the abutment block, taken on the line 3—3 of Fig. 1.

Fig. 4 is a vertical sectional view taken on the line a—a thereof, and a plan view, partially in section, of the adjustable clamp.

Fig. 5 is a diagrammatic view, showing the position of parts before and after bending a strip of metal, the latter position being shown in dotted lines.

Fig. 6 is a vertical sectional view taken on the line 6—6 of Fig. 2.

Fig. 7 is a vertical sectional view of the metal guide and a part of the machine on the line 7—7 of Fig. 5.

Fig. 8 is a perspective view of the metal guide.

Fig. 9 is an enlarged perspective view of the adjustable die holding mechanism.

Fig. 10 is a perspective view of the lower 55 sliding part of the machine.

Referring now in detail to the drawings, the frame-work of the machine constitutes the U-shaped base 1, its standard 2 extending upward, the fixed bending arm 3 attached to the standard 2, and a pivoted bending arm 4 operated by hand or power. The lower end of the standard 2 forms a solid bearing 5 for the heavy fulcrum pin 6 of the bending arm 4. The upper portion 60 of the standard 2 ends in a shorter fulcrum pin 7 upon which the top part 8 of the bending arm 4 pivots, affording an easy and precise adjustment of the parts.

Both the fixed and the pivoted bending 70 arms consist of a double bar arrangement 9 and 10 extended sideways and forming a guideway 11, terminating in heads 12 and 13. Slidable in said guideway, formed by the bars 9 and 10, are the adjusting blocks 75 14, provided with a longitudinal opening 15, for the clamp bolt 16, passing through an adjusting plate 17 having pins 18 registering with holes 19 of the bars 9 and 10 to enable a rough adjustment of the adjusting 80 blocks 14.

The precise and final adjustment of the metal bars to be bent is accomplished by an upwardly extending bracket 20 of the adjusting plate 17 which is provided with an 85 adjustment bolt 21; the adjusting blocks 14 can be moved toward or from each other for fine adjustment in a longitudinal direction by turning the bolt 21, the slot 15 allowing ample play for the clamp bolt 16, which, 90 after final adjustment is made, tightens all adjustable parts. These arrangements are similar on both the fixed and pivoted bending arms and may be changed as is expedient in the practice of similar construction.

In order to secure a firm hold of the heated metal and especially to prevent a bulging of the same, there are provided guides 22, as shown in Figs. 5 and 7 and 8. These guides are slidably mounted between the bars 9 and 10 and may have any form or shape adaptable to the kind of metal to be bent.

Secured to the front bar 9 of the fixed bending arm and near to the bearing 5 to extend outward, is a bracket 24 with a swallow-tail head 25, in which a slide 26 moves in parallel direction to the guide-way 11. One end of the slide 26 is bent upward as

shown in Fig. 10, the bent end 27 carrying a bar 28 secured by bolts 29. On the opposite side and attached to the upper surface of the slides 26, rests an angular bracket 30, fastened with bolts to the slide.

5 A bar 31, similar to that secured to the upward bent portion of the slide, is bolted to the bracket 30 with bolts 32. Bars 28 and 31 on one side, and the upwardly bent portion 27, the bracket 30 and the top surface 33 of the slide 26, between the bracket and the upwardly bent portion 27, on the other side, form a firm guide for a transverse slide 34. The portion nearest to the guide-way 10 11 of the slide 34 forms a head 35 provided with bolts 36, with which the die 37 is secured to the head 35. The shape and form 15 of the die correspond to the shape of the metal to be bent, as indicated in Figs. 6 and 9.

20 A lug 38 is formed with the head 35, on both sides of which two connecting rods 39 are pivotally attached at one end, the other end being also pivotally secured to a lug 40, extending from the middle of the operating shaft 41, which has its bearings in the upwardly extending portion of the guides 27, 28, 30, and 31. The shaft 41 can be easily operated by power or by 25 means of a handle 42. The procedure in bending a metal bar on the machine thus described is very simple and is indicated in Fig. 5.

30 After having been heated sufficiently in the vicinity of the bend to be made, the metal bar is placed in the guides 22, which are brought as close as possible to the bending point in order to prevent bulging of the metal. Adjusting blocks 14 are shifted 35 toward both ends of the bar, the fine adjustment being made through adjusting bolts 21, and then the adjusting or abutment blocks are firmly secured by the clamp bolts 16. The die 37 is next pressed against 40 the heated portion of the bar, the opposite side of which rests against the plate 43, attached to both of the bending arms 3 and 4. Then the pivoted bending arm 4 is swung 45 forward, bending the bar to the required angle.

50 The above process, but especially the novel feature of a simultaneous pressure playing on the die against the heated portion of the metal at the same time the actual bending process is taking place, not only facilitates the bending operation to a great extent, but obviously strengthens and shapes 55 the bent portion of the bar and affords an exact predetermination of both the lengths 60 of either of the legs forming the angle, and the angle itself. The strengthening of the bend is caused by the peculiar arrangement and working method of the bending mechanism.

65 In applicant's method, using his machine,

the outer fibers of the metal at the point of bending, are merely bent, and all the inner fibers are compressed. This is not so in ordinary methods, for ordinarily the outer fibers are stretched, the inner fibers are 70 compressed, and a single layer of fibers at the center remain unaffected. It is for the aforesaid reason that applicant's method strengthens the metal at the bending point.

Having thus described my invention, what 75 I claim and desire to secure by Letters Patent is as follows:

1. A metal bending machine comprising a base, a hollow standard mounted upon said base, a fixed arm having a longitudinal 80 guideway therein secured to said standard, a vertical shaft extending through said standard and having a movable arm attached thereto, said movable arm having a longitudinal guideway therein, adjusting 85 blocks slidably mounted in each of said guideways and each comprising a substantially T shaped member having a vertical substantially central channel extending therethrough, a substantially L shaped member adjacent said T shaped member and having a hole through the base thereof under the lower end of said channel, a screw passing through said channel and said hole so as to tie said L shaped member and said T shaped member together, an adjusting screw 90 mounted in the vertical arm of said L shaped member and having its tip contacting with said T shaped member, means for releasably securing said blocks at any desired point 95 in their respective guideways, and releasable means for holding the metal to be bent in secure position at the point about which the bend is to be made.

2. A metal bending machine comprising 105 a base, a hollow standard mounted upon said base, a fixed arm having a longitudinal guideway therein secured to said standard, a vertical shaft extending through said standard and having a movable arm attached thereto, said movable arm having a longitudinal guideway therein, adjusting 110 blocks slidably mounted in each of said guideways and each comprising a substantially T shaped member having a vertical 115 substantially central channel extending therethrough, a substantially L shaped member adjacent said T shaped member and having a hole through the base thereof under the lower end of said channel, a screw 120 passing through said channel and said hole so as to tie said L shaped member and said T shaped member together, an adjusting screw mounted in the vertical arm of said L shaped member and having its tip contacting with said T shaped member, means for releasably securing said blocks at any desired points in their respective guideways 125 comprising a plurality of recesses in the undersides of the said arms, and a plurality 130

5 of pins extending upward from the base of said L shaped member, said pins adapted to engage said recesses, and means for holding the metal to be bent in secure position at the point about which the bend is to be made.

10 3. A metal bending machine comprising a base, a hollow standard mounted upon said base, a fixed arm having a longitudinal guideway therein secured to said base, a vertical shaft extending through said standard and having a movable arm attached thereto, said movable arm having a longitudinal guideway extending therein, adjusting blocks 15 slidably mounted in each of said guideways, means for releasably securing said blocks at any desired point in their respective guideways, means for releasably and securely holding the metal to be bent comprising a bracket fixed to the forward part of 20 said fixed arm near said standard, a trough therein running parallel to said fixed arm, a flat bar slidably mounted in said trough, rigid spaced apart members mounted upon said bar at right angles to said trough and providing a guideway in the latter direction, a second flat bar slidably mounted in said last-named guideway and having a die holder rigid to one end, a shaft pivotally supported between said rigid members, links connecting said die holder and said shaft, and means for rotating said shaft.

25 4. A metal bending machine comprising a base, a hollow standard mounted upon said base, a fixed arm having a longitudinal guideway therein secured to said base, a vertical shaft extending through said standard and having a movable arm attached thereto, said movable arm having a longitudinal guideway extending therein, adjusting blocks 30 slidably mounted in each of said guideways, metal holding and guiding means mounted slidably in said guideways and comprising substantially U shaped members having depending bases engaging said guideways and troughs adapted to receive the metal to be bent, additional means for releasably and securely holding said metal comprising a bracket fixed to the forward 35 part of said fixed arm near said standard, a trough therein running parallel to said fixed arm, a flat bar slidably mounted in said trough, rigid spaced apart members mounted upon said bar at right angles to said trough and providing a guideway in the latter direction, a second flat bar slidably mounted in said last-named guideway and having a die holder rigid to one end, a shaft pivotally supported between said rigid 40 members, links connecting said die holder and said shaft, and means for rotating said shaft.

45 5. A metal bending machine comprising a base, a hollow standard mounted upon said base, a fixed arm having a longitudinal

guideway therein secured to said base, a vertical shaft extending through said standard and having a movable arm attached thereto, said movable arm having a longitudinal guideway extending therein, means for releasably and securely holding the metal to be bent comprising a bracket fixed to the forward part of said fixed arm, a trough therein running parallel to said fixed arm, a flat bar slidably mounted in said trough, rigid spaced apart members mounted upon said bar at right angles to said trough and providing a guideway in the latter direction, a second flat bar slidably mounted in said last-named guideway and having a die holder rigid to one end, a shaft pivotally supported between said rigid members, links connecting said die holder and said shaft, and means for rotating said shaft.

50 6. A metal bending machine comprising a base, a hollow standard mounted upon said base, a fixed arm having a longitudinal guideway therein secured to said standard, a vertical shaft extending through said standard and having a movable arm attached thereto, said movable arm having a longitudinal guideway therein, adjusting blocks 55 slidably mounted in each of said guideways and each comprising a substantially T shaped member having a vertical substantially central channel extending therethrough, a substantially L shaped member adjacent said T shaped member and having a hole through the base thereof under the lower end of said channel, a screw passing through said channel and said hole so as to bind together said L shaped member and said T shaped member, adjustable means mounted in the upper part of the vertical 60 arm of said L shaped member and contacting with said T shaped member, and releasable means for holding the metal to be bent in secure position at the point about which the metal is to be bent.

65 7. A metal bending machine comprising a base, a hollow standard mounted upon said base, a fixed arm having a longitudinal guideway therein secured to said standard, a vertical shaft extending through said standard and having a movable arm attached thereto, said movable arm having a longitudinal guideway therein, adjusting blocks 70 slidably mounted in each of said guideways and each comprising a substantially T shaped member having a vertical substantially central channel extending therethrough, a substantially L shaped member adjacent said T shaped member and having a hole through the base thereof under the lower end of said channel, a screw passing through said channel and said hole so as to hold together said L shaped member and said T shaped member, an adjusting screw 75 mounted in the vertical arm of said L 80

shaped member and having its tip contacting with said T shaped member, means for releasably securing said blocks at any desired point in their respective guideways 5 comprising a plurality of recesses in the undersides of said arms, and a plurality of pins extending upward from the base of said L shaped member, said pins adapted to engage said recesses, and means for releasably and securely holding the metal to be bent comprising a bracket fixed to the forward part of said fixed arm near said standard, a trough therein running parallel to said fixed arm, a flat bar slidably mounted

in said trough, rigidly spaced apart members 15 mounted upon said bar at right angles to said trough and providing a guideway in the latter direction, a second flat bar slidably mounted in said last-named guideway and having a die holder rigid to one end, 20 a shaft pivotally supported between said rigid members, links connecting said die holder and said shaft, and means for rotating said shaft.

Signed at New York, in the county of 25 New York and State of New York, this 30th day of August, A. D. 1919.

CHARLES DECRETTE.
